UNITED STATES PATENT OFFICE.

JOSEPH M. VAIL, OF BRYAN, OHIO.

RAIL-STAY.

1,074,667.

Specification of Letters Patent.

Patented Oct. 7, 1913.

Application filed May 23, 1913. Serial No. 769,379.

To all whom it may concern:

Be it known that I, JOSEPH M. VAIL, a citizen of the United States, and a resident of Bryan, in the county of Williams and State of Ohio, have invented a certain new and useful Rail-Stay; and I do hereby declare the following to be a full, clear, and exact description of the invention, such as will enable others skilled in the art to which it applies to make and use the same, reference being had to the accompanying drawings, and to the characters of reference marked thereon, which form a part of this specification.

15 This invention relates to devices adapted for use in conjunction with railway rails and the supporting ties therefor to prevent a relative creeping of the rails and ties, but is not restricted to such use, as it may be used in any connection for which it may be adapted or appropriate.

20 The object of my invention is the provision of a one-piece device of this character which is simple and inexpensive in its construction and capable of being easily and quickly applied to a rail base without the use of bolts or other retaining means, and also removed therefrom, and which is automatically operable to firmly clamp the 25 rail upon a creeping movement of the rail in one direction relative to an associated supporting tie, whereby the rail and tie are caused to have creeping movements together.

30 The invention is fully described in the following specification, and while, in its broader aspect, it is capable of embodiment in numerous forms, a preferred embodiment thereof is illustrated in the accompanying drawings, in which,—

35 Figure 1 is a plan view of portions of a rail and supporting tie therefor equipped with my invention, and Fig. 2 is an enlarged perspective view of the device.

40 Referring to the drawings, 1 designates a railway tie, and 2 a rail supported thereby, to the base of which a device comprising the invention is clamped. This device comprises a bar or body member 3, which is intended to extend beneath a rail from one side to the 45 other thereof, preferably in substantially flat contact with its base, and is provided at one end with a clamping head or jaw 4 for engaging around one side edge of the rail base. The head 4 is disposed trans-

versely of the bar 3 and has one end preferably projected beyond the bar, as shown.

50 A spring bar 5 extends from the projected end of the head 4 in the general direction of projection of the body member 3 from such head, and is of sufficient length to adapt it to extend from one side to the other of a rail base beneath the same, and has its free end terminating in a jaw or head 6 for clamping a rail base in opposition to the head 4, as shown in Fig. 2. The 55 bar 5 is preferably but not necessarily integrally connected at its inner end to the head 4, and is provided intermediate its ends with one or more loops 7, or is otherwise suitably formed, to adapt it to have 60 yielding lengthening movements relative to the body member 3 and head 4 to facilitate a springing of one or the other of the clamping heads 4 and 6 into or out of engagement with a rail base when the other 65 clamping head is engaged with the opposite edge of the base, and also to adapt its free end to have lateral yielding movements 70 relative to the body member 3.

75 The clamping head 6 projects toward the free end portion of the body 3, and has its outer side longitudinally tapered and notched in stepped form, as indicated at 8, the taper being such as to retract the head from its outer end inwardly. The free end 80 of the body member 3 is provided with a hook part 9, which is adapted to extend around the notched surface 8 of the clamping head 6 and to coöperate with one of the notches thereof to retain the head 6 in firm 85 clamping engagement with the edge of the rail base when pressure is applied against the outer side of the thrust arm 10, which 90 arm projects from the outer side of the head 4 and is adapted to abut at its outer 95 end against the adjacent side of the tie 1. The concaved or inner side of the hook 9 is of sufficient depth relative to the point thereof to permit the enlarged or tapered portion of the head 6 to be sprung outwardly therein sufficiently to release such head from engagement with the rail base when the free end of the spring bar 5 is sprung inwardly adjacent to the bar 3. The 100 hook 9 thus serves not only to draw the head 6 into clamping engagement with the rail base, but also to limit the outward springing movements of the head 6 relative 105

to the head 4 so as to prevent a possibility of the spring bar 5 being broken in two upon too great an outward springing or lengthening of the same, which might occur with 5 careless workmen.

In the use of this device it is engaged with the base of a rail at the near side of the tie in the direction of creeping action of the rail, in position for the abutment 10 10 of the head 4 to have contact with the tie side, whereby a creeping movement of the rail will cause the engaged end of a tie to have corresponding movement therewith. In applying one of my devices to a rail, it 15 is placed under the base thereof with the head 4 in engagement with one side edge of the base, and the clamping head 6 is then sprung outward a sufficient extent to enable it to be engaged around the opposite 20 edge of the rail base. The contractile action of the spring connection between the clamping heads 4 and 6 is sufficient to normally retain such heads in yielding clamping engagement with the rail base, and at 25 the same time is adapted to permit a yielding movement of the body bar 3 longitudinally of the rail relative to the spring bar 5. In placing a device in engagement with a rail, the abutment 10 should be placed in 30 contact with the side of a tie toward which the rail may have a tendency to creep, as shown in Fig. 1. Upon a creeping action of the rail the abutment 10 has its thrust against the tie so that the tie opposes a 35 creeping movement of such bar, thus tending to force the end of the head 4 from which the spring bar 5 projects in clamping engagement with the rail base due to the outward projecting of the abutment 10 from 40 the outer side of the head 4. In other words, the body bar 3, head 4 and thrust arm or abutment 10 act as a lever with the end portion of the head adjacent to the spring bar fulcruming against the rail base. The 45 movement which is imparted to the head 4 upon the application of pressure to the outer end of the thrust arm 10 causes a drawing of the body member or bar 3 transversely of the rail base and causes its hooked end to act against the clamping head 6 to hold it in firm rail clamping position in 50 opposition to the head 4 so that any further creeping action of the rail will be positively communicated to the tie.

55 For the purpose of durability and cheapness of construction it is preferable to cast my improved device in a single piece from malleable iron, as such metal is sufficiently yieldable in its nature to permit of a relatively yielding action of the clamping heads and also of the bars 3 and 5.

It will be understood, however, that the invention is not limited to the use of any particular material or to the construction of 60 the device in a single integral piece or in 65

the particular form shown, except in so far as such limitations are specified in the claims.

Having thus described my invention, what I claim as new, and desire to secure by Letters Patent, is,

1. A device of the class described having a pair of yieldingly connected opposed rail base clamping parts, and a bar and a thrust arm projecting from one of said parts, the bar being movable transversely of a clamped rail base and caused to impart a rail clamping action to one of said parts when pressure is applied in one direction to the thrust arm.

2. A device of the class described having a plurality of yieldingly connected cross-bars, rail base clamping parts carried by said bars and a thrust-member projecting from the connected end portions of said bars and operable upon an application of pressure thereto in one direction to longitudinally move one of said bars to effect a clamping action of said parts against an engaged rail base.

3. A device of the class described having opposed yieldingly connected rail clamping parts, a body member projecting from one of said parts transversely of a rail and having its free end shaped and positioned to have engagement with the outer side of the other of said clamping parts to cause it to have a rigid rail clamping action when said body member is moved in one direction transversely of a rail, and a thrust-arm projecting from the clamping part from which said body member projects and movable by pressure thereon in one direction lengthwise of a rail to impart part clamping movements to said member.

4. A device of the class described having a body member projecting transversely under a rail base, said body member having one end hooked and its free end provided with a rail base clamping part, a spring member projecting from said part in the direction of projection of said body member and having a part for yieldingly clamping a rail base in opposition to said first part, and means movable by tie thrust action to move said body member transversely of a rail and to cause its hooked end to act on the clamping part of said spring bar to hold it in firm rail clamping position.

5. A device of the class described having a lever member extending under a rail base and adapted to have thrust contact with a side of a tie at one side of a rail base, said member having a part adjacent to its tie abutting end for engaging an edge of a rail base and having its opposite end angled, and an element for clamping a rail base in opposition to said part and caused to be held in firm rail base clamping position when pressure is applied in one

direction on the tie abutting end of said member.

6. A device of the class described having a lever member extending under a rail base 5 and adapted to have thrust contact with a side of a tie at one side of a rail base, said member having a part adjacent to its tie abutting end for engaging an edge of a rail base and having its opposite end angled and 10 an element yieldingly connected to said part and caused to be held in firm rail base clamping position when pressure is applied in one direction on the tie abutting end of said member.

15 7. A device of the class described comprising yieldingly-connected opposing rail base clamping parts, a bar projecting from one of said parts and having its free end in adjustable engagement with the outer side 20 of the other of said parts and a thrust member projecting from the part from which

said bar projects and caused to exert a draft action on said bar to move said parts into firm rail clamping engagement when pressure is applied in one direction on said member.

25 8. A device of the class described having a pair of yieldingly-connected opposed rail base clamping parts, and means for limiting the relative outward springing movements of said parts and operable to cause 30 said parts to have firm rail clamping engagement when pressure is exerted on a portion of said means.

In testimony whereof, I have hereunto signed my name to this specification, in the presence of two subscribing witnesses.

JOSEPH M. VAIL.
